UNITED STATES PATENT OFFICE.

SAMUEL S. SENCENBAUGH AND ALBERT J. IVES, OF AURORA, ILLINOIS.

DESIGN FOR AN UMBRELLA-STAND.

SPECIFICATION forming part of Design No. 22,568, dated June 27, 1893.

Application filed May 29, 1893. Serial No. 475,972. Term of patent 3½ years.

To all whom it may concern:

Be it known that we, SAMUEL S. SENCENBAUGH and ALBERT J. IVES, citizens of the United States, residing at Aurora, in the county of Kane and State of Illinois, have invented a new and original Design for Umbrella-Stands, of which the following is a specification.

The invention relates to a new and original design for umbrella stands.

The object of the present invention is to provide an ornamental umbrella stand which will present a neat and attractive appearance; and the essential feature resides in an umbrella stand having an ornamental tripod base, a scalloped bowl supported on the base, a twisted standard rising from the center of the bowl and having an ornamental top or head, and a circular holder.

The figure of the drawing is a perspective view of an umbrella stand, showing our original design.

Referring to the drawing, 1 designates a tripod base having ornamental legs 2, and above the base is located a bowl 3. The bowl

3 has a scalloped upper edge and is provided with radial raised ribs 4 on its upper face. The ribs form intermediate concave sector-shaped portions and extend upward and outward from a central polygonal socket 5. A 30 twisted or spirally-grooved standard 6 rises from the socket and is provided, at its top, with an ornamental head 7. An umbrella holder 8 is arranged near the upper end of the standard; it is circular and is provided 35 with an annular series of umbrella rings 9.

It will be apparent that the umbrella stand is highly ornamental and presents an attractive appearance.

What we claim is—

The design for umbrella stands herein shown and described.

In testimony that we claim the foregoing as our own we have hereto affixed our signatures in the presence of two witnesses.
